Primary Examiner — Eric Goodman*Assistant Examiner* — Luqman McNeil*(74) Attorney, Agent, or Firm* — Sheridan Ross P.C.(57) **CLAIM**

The ornamental design for a pressure washer, as shown and described.

DESCRIPTION

FIG. 1 is a front perspective view of the pressure washer;

FIG. 2 is a top plan view thereof;

FIG. 3 is a front elevation view thereof;

FIG. 4 is a left elevation view thereof;

FIG. 5 is a right elevation view thereof; and,

FIG. 6 is a rear elevation thereof.

The broken lines showing a pressure washer are included for the purpose of illustrating environment and form no part of the claimed design.
